UNITED STATES PATENT OFFICE.

WILLIAM C. COLLIGNON, OF CHICAGO, ILLINOIS, ASSIGNOR TO THE CABLE COMPANY, OF CHICAGO, ILLINOIS, A CORPORATION OF ILLINOIS.

PNEUMATICALLY-OPERATED MUSICAL INSTRUMENT.

Application filed March 31, 1924. Serial No. 703,071.

This invention relates to pneumatically operated musical instruments, and more particularly concerns the adjustable regulation and automatic control of the air-pressure employed in the operation of such instruments.

The principal object of the invention is to provide a device for use in connection with the air-pressure-supply systems of pneumatically operated musical instruments (1) which will co-operate therewith in the provision of a sufficient and substantially constant degree of air-pressure for the proper pneumatic operation of certain instrument-parts and, at the same time, permit desired variations to be made in the degree of the air-pressure which is employed in the pneumatic operation of other instrument-parts, and (2) which will permit the pneumatic operation of any of said instrument-parts to be properly effected without interfering with the proper pneumatic operation of any other of said instrument-parts.

A further object of the invention is to provide such a device which shall be efficient in action and of simple and inexpensive construction.

In the drawings:—

Figure 1 is a front and partly sectional view of a pneumatically operated piano embodying this invention, the showing being somewhat diagrammatic and fragmentary in places;

Fig. 2 is a detail, in vertical transverse section, of a control-box, taken upon the line 2—2 in Fig. 3;

Fig. 3 is a detail, in vertical longitudinal section, of the same control-box, taken upon the line 3—3 in Fig. 2; and

Fig. 4 is a detail, in vertical longitudinal section, of a conventional form of motor control-valve-box.

The invention is shown and will be described in connection with a pneumatically operated piano, in which the note-sounding hammers are actuated in the usual or any desired manner by what are commonly termed "striker-pneumatics" and in which other elements of the instrument, such as the hammer-rest-rails and the damper-lift, are individually operated by other pneumatics. It is customary to provide instruments of this character with means for controllably varying the power of the playing-pressure (i. e., the degree of the air-pressure supplied

for the operation of the striker-pneumatics), so that desired musical expression effects may be obtained, during the playing of a musical selection, by varying in this manner the power with which the note-sounding hammers are actuated.

It frequently happens that, in order to obtain the softer or lighter playing effects, the power of the playing-pressure is so reduced as to be insufficient to accomplish the proper and positive operation of the hammer-rest-rail and damper-lift pneumatics, and it also frequently happens that, during such softer or lighter playing, each pneumatic operation of the hammer-rest-rail and the damper-lift causes a very noticeable and undesirable further weakening of the playing-pressure, in some instances resulting in a complete, though temporary, silencing of the notes. It might be perfectly feasible to remedy the first of these two mentioned objectionable conditions by employing hammer-rest-rail and damper-lift pneumatics of comparatively greater surface-area, thereby applying the weak playing-pressure with greater power for the operation of these devices, if it were not for the fact that such a remedy for the first-mentioned condition would add to and render even more noticeable and objectionable the second-mentioned condition; that is to say, if larger pneumatics were employed for the operation of the hammer-rest-rails and the damper-lift, such larger pneumatics would require a proportionately greater volume of air-pressure for their operation, and the use of such greater volume of air-pressure for their operation, during the aforesaid softer or lighter playing, would still further deprive or "rob" the striker-pneumatics of their already reduced operating power.

Certain well-known types of pneumatically operated pianos are provided with pressure-supply systems which include a reservoir and one or more pressure-reducing governors or regulators, and in such instruments the power of the playing-pressure may be controllably varied to some extent and may be reduced to obtain the softer or lighter playing effects, without necessarily effecting simultaneous and equal variations in the degree of air-pressure which is held in reserve in the reservoir and which is therefore available for the operation of the hammer-rest-rail and damper-lift pneumatics.

ics. However, in the type of instrument for which this invention is designed and in which it is especially useful, the employment of a reservoir is unnecessary and even undesirable, since it would interfere with the obtaining of desired sharp and sometimes extreme variations in the power of the playing-pressure. This last-mentioned type of instrument is too well known to require or warrant an exhaustive description of its qualifications, as compared with those of the first-mentioned type. It is sufficient to state at this point that, through the employment of means hereinafter described and claimed, the desirable effects obtainable in the first-mentioned type of instrument, through the use of a reservoir and a more or less complicated and expensive pressure supply and control system, are equally obtainable here without a reservoir and without sacrificing, or in the least degree interfering with, the production of other desirable effects obtainable in the second-mentioned type of instrument, including the aforesaid sharp and extreme variations in the power of the playing-pressure.

Referring now to Figure 1 of the drawings, the instrument therein shown constitutes what is known as a "reproducing piano", although it may be operated as a foot-pumped player-piano as well. When used as a reproducing piano, the operating air-pressure is supplied by a motor-driven exhaust-pump and the control of the various instrumentalities is effected from the music-sheet while, when used as a regular player-piano, the operating air-pressure is supplied by foot-operated exhausters and the control of the various instrumentalities is effected by the operator through the foot-operation of such exhausters and the manipulation of certain control-levers. The usual reservoir is provided for co-operation with the foot-operated exhausters, but this reservoir is arranged to be automatically disconnected by the operation of the motor-driven exhaust-pump. The instrument comprises a player-action 1, having the usual or any desired form of music-sheet-controlled valve-actions and striker-pneumatics for actuating the piano-hammers; a tracker-box 2, in which are housed the tracker 3, the music-roll-supports 4 and 5, and the take-up spool 6, for winding the music-sheet from its roll 7 and drawing it across the tracker in the usual manner and for the usual purposes; a music-sheet-propelling wind-motor 8, together with its controlling-valve-box 9 and pressure governor or regulator 10; hammer-rest-rail pneumatic units 11 and 12, for controllably operating the usual treble and bass sections of the hammer-rest-rail to change the travel or stroke-length of the respective treble and bass groups of piano-hammers; damper-lift (sustaining pedal) pneumatic unit 13, for

controllably operating the piano-string-dampers; a motor-driven exhaust-pump 14, for exhausting a substantially uniform volume of air to supply operating power for the various pneumatically operable instrumentalities; a pressure-controlling device 15, for controllably varying the power of the playing-pressure (i. e., the degree of air-pressure produced in the player-action by the operation of the exhaust-pump) by the admission of varying quantities of atmospheric air, which admission is automatically governed or regulated by the device under manual or music-sheet control, or both; and a valve-chest 16, in which are preferably located the primary valves which serve to control the operation of the hammer-rest-rail pneumatic units, the damper-lift pneumatic unit, the pressure-controlling device, and any other desired pneumatically operable instrumentalities, and which primary valves are themselves controlled in operation either manually or automatically from the music-sheet, or both manually and automatically, as desired.

In addition to the devices just described, which enter into the automatic operation and control of the instrument as a reproducing piano, exhausters 17 and 18 and reservoir 19 are indicated by dotted lines as being positioned upon the rear side of the board 20. Valve-box 21 is shown as provided with a conventional form of action-cut-off valve 22, which is connected for manual operation by the usual rewind-lever 23. In order to avoid further and unnecessary complication of the drawings, treadles for operating the exhausters 17 and 18 have not been shown and the usual pneumatic connection of exhausters 17 and 18 with the motor valve-box 9 has been omitted. The construction and arrangement of these parts are so well known that a showing and description thereof are believed unnecessary. Arranged within the reservoir 19, is a cut-off valve 24, which is connected with a pneumatic 25 and adapted to be operated by the collapse thereof to close the passage connecting the reservoir with the pressure-supply system. Pneumatic 25 is in constant communication with the exhaust-pump 14, through a tube 26, so that operation of the exhaust-pump will cause immediate collapse of the pneumatic, thereby closing the cut-off valve and disconnecting the reservoir from communication with the pressure-supply system.

Positioned preferably directly upon the top of exhaust-pump 14, is a control-box or chest 27 which controls the entire volume of air exhausted by the pump. Chest 27 is horizontally divided by a partition 28 into upper and lower chambers 29 and 30, respectively. Upon reference to Fig. 2, it will be seen that the chamber 30 is wider than the chamber 29, and that the partition

28 is provided with a port 31 which is outside of the chamber 29 and constitutes an atmospheric inlet for the chamber 30. Chamber 30 communicates with the wind-way 32 of the exhaust-pump through a passage 33, and the admission of atmospheric air through the port 31 into chamber 30 is resisted by an inwardly opening, spring-pressed valve 34 of any desired construction. As herein shown, the valve 34 is hingedly secured to the partition 28 and is forced upwardly to cover the port 31 by one end-part of a flat spring 35. Spring 35 is pivotally supported intermediate its ends upon a screw 36, so that one end-part of the spring may bear upwardly with valve-closing effect upon the valve 34 and the other end-part thereof will be positioned beneath and offered to the compressing effects of an adjusting screw 37. Lateral swinging displacement of the spring is prevented by guide-pins 38. The operation and adjustment of this simple form of "overblow" valve is apparent. If at any time the volume of air which is being constantly and uniformly exhausted by the pump exceeds the amount admitted to chamber 30 through the operation of the various pneumatically operable instrumentalities, the degree to which the air-pressure will be reduced in the chamber 30 will be determined by the resistance offered by valve 34 to the admission of atmospheric air, and this resistance may be controlled by adjustment of the screw 37 to increase or decrease the strain thereby placed upon spring 35. Adjustment of screw 37 will determine the maximum working load to be placed upon the exhaust-pump 14.

Partition 28 is also provided with a port or passage 39 through which chamber 29 may communicate with chamber 30, such communication being controlled by a valve 40. Valve 40 is herein shown as a slide-valve, guided for movement over and from the port 39 by a wire-staple guide 41, which co-operates with a slot 42 in the top of the valve. A valve-rod 43 is shown as hooked into the valve and extending outwardly through the side of chest 27 for connection with valve-operating means to be later described. The particular construction of valve 40, together with the means for and method of its operation, may be varied as desired, its simple purpose being to control the communication of chamber 29 through port 39 with chamber 30. Chamber 30 is provided with an inlet 44, and a conduit 45 connects this inlet with the motor valve-box 9.

Chamber 29 is provided with an inlet 46, and a branched conduit 47 connects this inlet, through branch 48, with the treble hammer-rest-rail pneumatic unit 12; through branches 49 and 50, with the primary valve-

chest 16; through branches 49 and 51, with the damper-lift pneumatic unit 13; and through branches 49, 51 and 52, with the bass hammer-rest-rail pneumatic unit 11. Opening into the top of chamber 29, is a valve-controlled inlet port or passage 53, and a branched conduit 54 connects this port, through branch 55, with the pressure-controlling device 15 and, through branch 56, with connected passages leading from the player-action 1. These connected passages include the conduit 57, leading from the player-action to valve-box 21; the port 58, controlled by action-cut-off valve 22 and leading from the valve-box to the trunk 59 of the foot-operated exhaust-pump unit; and the port 60, controlled by a check-valve 61 and opening into the aforesaid conduit-branch 56. Check-valve 61 opens toward the motor-driven exhaust-pump 14 and closes whenever air-pressure is reduced in trunk 59 to a greater degree than it is reduced in the conduit-branch 56. It will be seen, therefore, that air cannot enter past the check-valve 61 from the pressure-controlling device 15 or the exhaust-pump 14 to interfere with the foot-operation of exhausters 17 and 18, when the instrument is being used as a foot-pumped player-piano, and it will also be understood that the foot-operated exhausters may be employed to increase the power of the playing-pressure while the motor-driven exhaust-pump is in operation. This last-mentioned condition obtains whenever it is desired to employ the motor-driven exhaust-pump as an auxiliary to the foot-operated exhausters during the use of the instrument as a foot-pumped player-piano, and it also obtains whenever it is desired to employ the foot-operated exhausters to give additional accent or emphasis to a portion of a musical selection when the instrument is being used as a reproducing piano.

Admission of air to the chamber 29 through port 53 from the pressure-controlling device 15 or the player-action 1 is resisted by an inwardly opening, spring-pressed valve 62 of any desired construction. Like valve 34, this valve 62 is shown as hingedly secured in position and forced upwardly to close its port 53 by one end-part of a spring 63, but the construction and arrangement of the spring is somewhat different from that of spring 35. Valve 62 is in constant play during the operation of the motor-driven exhaust-pump and the playing of the instrument and, in order to avoid objectionable noise which might result from friction between the spring and the valve, a link-connection is employed, comprising the link 64 and a screw-hook 65. Spring 63 is of wire and is supported between its ends upon a screw 66, preferably being secured in position by having the screw transfix a

couple of helical turns in the wire. At the heel-end of the spring, the wire is bent sharply to form a prong or hook which engages within the cup of a cup-pointed adjusting screw 67. The operation and adjustment of this valve 62 will be later described.

As hereinbefore stated, when the instrument is used as a regular player-piano, the operating air-pressure is supplied by foot-operated exhausters (17 and 18) and the control of the various instrumentalities is effected by the operator through the foot-operation of such exhausters and the manipulation of certain control-levers. Rewind-lever 23 and tempo-lever 68 are two such control-levers. In addition to its connection, through a tie-rod 69 and lever 70, with the action-cut-off valve 22, rewind-lever 23 is connected, by a tie-rod 71, with the usual motor rewind-valve 72 (Fig. 4), located in motor valve-box 9 and controlling a "high wind" or "unregulated air" passage or port 73, such as is customarily provided to enable rapid rewinding of the music-sheet to be obtained. Tie-rod 71 extends through the motor-valve-box 9 and is attached to an arm 74 fixed upon the vertical shaft or roller 75. Connected with another arm 76 fixed upon the upper end-part of roller 75, is a tie-rod 77 which is operatively connected to the reversible music-sheet-propelling gearing.

Movement of rewind-lever 23 in one direction will move action-cut-off valve 22 to open the port 58 and establish pneumatic communication between player-action 1 and trunk 59 of the foot-operated exhaust-pump unit. It will also move motor rewind-valve 72 to close the port 73 and thereby cut off direct communication of wind-motor 8 with said trunk 59 through the usual conduit (not shown) and at the same time will effect the adjustment of the music-sheet-propelling gearing so that operation of wind-motor 8 will propel the music-sheet forwardly across the tracker 3. Adjustment of tempo-lever 68 will position the tempo-valve 78 to allow the desired amount of air to be drawn from wind-motor 8 through the usual tempo-slot 40 and the pressure governor or regulator 10, and thence through the aforesaid usual conduit (not shown), to trunk 59, and the operation of exhausters 17 and 18 will effect the forward propulsion of the music-sheet and the playing of the instrument. Movement of rewind-lever 23 in the reverse direction will reverse the position of valves 22 and 72 and the adjustment of the music-sheet-propelling gearing so that the operation of player-action 1 and the playing of the instrument will be discontinued and, if the operation of exhausters 17 and 18 continues, wind-motor 8 will be operated at increased speed to rewind the music-sheet upon its roll 7. The operative association of the

parts just described is old and well known. The purpose of such description will be apparent from that which follows.

Reproducing pianos are usually provided with devices which are controlled in operation either pneumatically from the music-sheet or mechanically from the music-spoils to automatically effect the playing and rewinding results just described in connection with rewind-lever 23, but such provisions contemplate either the use of a specially prepared music-sheet (a "reproducing record") or a more or less complicated arrangement of mechanical devices. It has been hereinbefore mentioned that the construction herein shown permits the employment of the motor-driven exhaust-pump as an auxiliary to the foot-operated exhausters during the use of the instrument as a foot-pumped player-piano and such a use of the exhaust-pump would imply the use of regular music-sheets, that is, music-sheets not provided with specially arranged perforations. Consequently, in order to illustrate the purpose of valve 40 when the exhaust-pump is to be used as an auxiliary, and in order to illustrate its operative association with alternate playing and rewinding of the music-sheet and with the acceleration in speed of the wind-motor 8 during rewinding, each of which features is common to all reproducing pianos as well as to player-pianos, the valve-rod 43 is shown connected, by link 79, with a third arm 80 fixed upon roller 75, at the lower end-part thereof. Now, with this arrangement, movement of rewind-lever 23 into "play" position will effect the opening of port 58, the closing of port 73, and the proper adjustment of the music-sheet-propelling gearing, all as aforesaid, and it will also move valve 40 to open port 39 and thereby establish pneumatic communication between chamber 29 and the exhaust-pump 14. The adjustment of screw 67 is such that spring 63 will resist the opening of valve 62 until the air-pressure in chamber 29 and the various instrumentalities already described as pneumatically connected with that chamber has been reduced to a sufficient degree for the proper and positive operation of such instrumentalities. When such a degree has been reached, valve 62 will be drawn open and air will be exhausted from the player-action 1 and the pressure-controlling device 15, through the hereinbefore described conduits and passages connecting them with the inlet port or passage 53. The power of the playing-pressure thus provided by the exhaust-pump will be determined by the pressure-controlling device, under either manual or music-sheet control, or both, but, even though the maximum amount of atmospheric air be admitted through such device and under such control, to reduce the power of the playing-pressure

- for the production of the softest or lightest playing effects, the operative power of the air-pressure in chamber 29 will not drop below the point determined by the adjustment of the screw 67, since, in order to be further reduced by the pressure-controlling device for playing effects, it must be sufficient to open and pass by the valve 62. As a consequence, the foot-operation of exhausters 17 and 18 need only be such as to produce the desired playing effects, and the playing effects thus produced may be extremely soft or light without affecting or being affected by the operation of the hammer-rest-rails or the damper-lift, the production of a sufficient (but non-interfering) degree of air-pressure for the proper operation of these and other instrumentalities being insured by the operation of the exhaust-pump and the action of valve 62. Movement of rewind-lever 23 into "rewind" position will reverse the positions of all of the parts hereinbefore described as connected with that lever, port 39 will be closed by the valve 40, and pneumatic communication of the exhaust-pump with chamber 29 and the various instrumentalities connected therewith through the branched conduits 47 and 54 will be interrupted. If the operation of the exhaust-pump is continued to effect the rewinding of the music-sheet, the foot-operation of the exhausters may, of course, be discontinued. With port 39 closed by the valve 40, the degree of air-pressure produced in chamber 30 and acting through conduit 45 and port 73 (in motor valve-box 9) upon wind-motor 8 will be determined by the adjustment of screw 37. This means that the full power of the exhaust-pump will be applied to the wind-motor 8, and the rewinding of the music-sheet upon its roll 7 may be as rapid as desired. The speed of such rewinding may be limited by restricting the passage of the air through port 73, either through the employment of a port of moderate size or through adjustment of the valve 72 upon tie-rod 71 so that, when opened, it will uncover a portion only of the port.
- Passing now to the use of the instrument as a reproducing piano, let it be assumed that the music-sheet to be employed is a "reproducing record" and that, as it is advanced across the tracker 3, special control-perforations provided in the margin thereof will co-operate with correspondingly arranged tracker-apertures to automatically control the operation of the several primary valves located in the valve-chest 16. As has been hereinbefore mentioned, certain of these primary valves serve to control the operation of the hammer-rest-rail and damper-lift pneumatic units 11, 12, and 13, respectively, and others serve to control the operation of the pressure-controlling device 15. Let it be assumed, for illustrative purposes only, that five different degrees of playing-pressure may be selectively provided through the operation of the pressure-controlling device 15 and that such degrees of playing-pressure have been predetermined by the adjustment of the device to be, respectively, 9, 11, 15, 19, and 35 inches, w. g. p. (water-gauge pressure). Furthermore, let it be assumed that the degree of air-pressure necessary for the proper and positive pneumatic operation of the hammer-rest-rails and the damper-lift is 13 inches, w. g. p. Under such conditions, the adjusting screw 37 might well be set to determine the resistance of valve 34 at 40 inches, w. g. p., and the adjusting screw 67 be set to determine the resistance of valve 62 at 15 inches, w. g. p.
- With rewind-lever 23 set at "play" position, the valve 40 will be open and, when the exhaust-pump is started, the degree to which the air-pressure will be reduced in chest 27, motor valve-box 9, pneumatic units 11, 12, and 13, and primary valve-chest 16 will be determined by the resistance of valve 62 at 15 inches, w. g. p., which is the degree assumed to be sufficient to properly and positively operate the several mentioned pneumatically operable instrumentalities. If the tempo-lever 68 be now adjusted to open tempo-valve 78 to effect the playing of the musical selection at a desired tempo, the air-pressure acting upon the wind-motor 8 to advance the music-sheet at the proper steady speed will be determined in the usual manner by the pressure governor or regulator 10. As the record continues to be advanced, the operation of the striker-pneumatics and their actuation of the note-sounding hammers will be controlled in the usual manner through the note-perforations in the record, and the power of the playing-pressure will be varied by the admission of varying quantities of atmospheric air through the pressure-controlling device 15 under the control of the special control-perforations provided for such purpose in the margin of the record.
- To produce the softer or lighter playing effects, the power of the playing-pressure will often be reduced to that of 9 or 11 inches, w. g. p. (the two lower degrees provided by the pressure-controlling device), but such reductions in the power of the playing-pressure may not materially reduce the power of the operating air-pressure existing in chamber 29 and in any of the pneumatically operable instrumentalities which are or might be connected with that chamber between valve 62 and the exhaust-pump. Although valve 62 will necessarily be open during the playing of the instrument to enable the exhaust-pump to provide playing pressure in the player-action, and although

the power of that playing-pressure may be sharply and extremely varied, the fact remains that the opening of that valve is accomplished through the reduction of air-pressure in the chamber 29 and communication of the player-action with the exhaust-pump is dependent upon the maintaining of a sufficient degree of air-pressure reduction in chamber 29 to keep valve 62 open against the resistance of spring 63. When the higher degrees of playing power are employed, the power of the operating air-pressure in chamber 29 will be increased accordingly but, under such conditions, the proper and positive operation of the several mentioned pneumatically operable instrumentalities are not endangered and need not be discussed.

I claim:—

1. In a pneumatically operated musical instrument, the combination, with a plurality of pneumatically operable instrumentalities (1—13), an exhaust-pump (14) for reducing the air-pressure to effect the pneumatic operation thereof, and pressure-controlling means (15) for admitting atmospheric air to vary the degree of reduced air-pressure available for the operation of certain of said instrumentalities (1), of means (34—62) for predetermining the maximum degree to which the air-pressure shall be reduced and the minimum degree to which the reduced air-pressure available for the operation of another of said instrumentalities (13) may be modified.
2. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure available for the operation of certain of said instrumentalities, of means (34) for predetermining the maximum degree to which the air-pressure shall be reduced, and means (62) for predetermining the minimum degree to which the reduced air-pressure available for the operation of another of said instrumentalities (13) may be modified by variations in the degree of reduced air-pressure available for the operation of said certain of said instrumentalities.
3. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure available for the operation of certain of said instrumentalities, of means for predetermining the maximum degree to which the air-pressure shall be reduced by said exhaust-pump, and

means for predetermining the minimum degree to which the reduced air-pressure available for the operation of another of said instrumentalities may be modified by the action of said pressure-controlling means 79 and the operation of said certain of said instrumentalities.

4. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure available for 80 the operation of certain of said instrumentalities, of means (34—62) for predetermining the maximum degree to which the air-pressure shall be reduced and for preventing 85 variations in the degree of reduced air-pressure available for the operation of said certain of said instrumentalities (1) from affecting beyond a predetermined minimum the degree of reduced air-pressure available for the operation of another of said instrumentalities (13).

5. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure available for 95 the operation of certain of said instrumentalities, of means (34—62) for predetermining the maximum degree and the minimum degree of reduced air-pressure which shall be available for the operation of another of said instrumentalities (13) while permitting 100 the degree of reduced air-pressure available for the operation of said certain of said instrumentalities (1) to be varied to exceed said minimum degree.

6. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure available for the operation of certain of said instrumentalities, of means (37—67) for separately and adjustably establishing the maximum degree to 110 which the air-pressure shall be reduced and the minimum degree to which the reduced air-pressure may be modified for the operation of another of said instrumentalities.

7. In a pneumatically operated musical instrument, the combination, with a plurality of pneumatically operable instrumentalities, an exhaust-pump for reducing the air-pressure to effect the pneumatic operation thereof, and pressure-controlling means 125

for admitting atmospheric air to vary the degree of reduced air-pressure available for the operation of certain of said instrumentalities, of means (37) for adjustably establishing the maximum degree to which the air-pressure shall be reduced, and means (67) for adjustably establishing the minimum degree to which the reduced air-pressure available for the operation of another 10 of said instrumentalities may be modified by variations in the degree of reduced air-pressure available for the operation of said certain of said instrumentalities.

8. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure available for the operation of certain of said instrumentalities, of means for adjustably establishing the maximum degree to which the air-pressure shall be reduced by said exhaust-pump, and means for adjustably establishing the minimum degree to which the reduced air-pressure available for the operation of another of said instrumentalities 25 may be modified by the action of said pressure-controlling means and the operation of said certain of said instrumentalities.

9. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure available for the operation of certain of said instrumentalities, of means (37—62) for adjustably establishing the maximum degree to which the air-pressure shall be reduced and for preventing variations in the degree of reduced air-pressure available for the operation of said certain of said instrumentalities (1) from affecting beyond a predetermined minimum the degree of reduced air-pressure 40 available for the operation of another of said instrumentalities (13).

10. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure available for the operation of certain of said instrumentalities, of means (37—67) for separately and adjustably establishing the maximum degree and the minimum degree of reduced air-pressure which shall be available for 60 the operation of another of said instrumentalities.

11. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure effective in one of said instrumentalities, of means for predetermining the maximum degree to which the air-pressure shall be reduced by said exhaust-pump, and means for preventing pressure variations effective in said one of said instrumentalities from varying, beyond a predetermined degree, the degree of reduced air-pressure effective in said exhaust-pump. 70

12. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure effective in one of said instrumentalities, of a pneumatic connection extending between said pressure-controlling means and said one of said instrumentalities on the one hand and said exhaust-pump on the other hand, means located in said connection and exposed to the air-pressure therein for yieldingly resisting the passage of air therethrough, an atmospheric inlet opening into said connection between the last said means and said exhaust-pump, and means for yieldingly resisting the admission of atmospheric air through 85 said inlet. 90

13. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure effective in one of said instrumentalities, of a pneumatic connection extending between said one of said instrumentalities and said exhaust-pump, means located in said connection and exposed to the pressure-varying effects of said pressure-controlling means for yieldingly resisting the passage of air through said connection, an atmospheric inlet opening into said connection between the last said means and said exhaust-pump, and means for yieldingly resisting the admission of atmospheric air through 100 said inlet. 105

14. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure effective in one of said instrumentalities, of a pneumatic connection extending between said one of said instrumentalities and said exhaust-pump, means located in said connection and exposed to the pressure-varying effects of said pressure-controlling means for yieldingly resisting the passage of air through said connection, an atmospheric inlet opening into said connection between the last said means and said exhaust-pump, and means for yieldingly resisting the admission of atmospheric air through 120 said inlet. 125

15. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure effective in one of said instrumentalities, of a pneumatic connection extending between said one of said instrumentalities and said exhaust-pump, means located in said connection and exposed to the pressure-varying effects of said pressure-controlling means for yieldingly resisting the passage of air through said connection, an atmospheric inlet opening into said connection between the last said means and said exhaust-pump, and means for yieldingly resisting the admission of atmospheric air through 130 said inlet. 135

- ties, an exhaust-pump for reducing the air-pressure to effect the pneumatic operation thereof, a pneumatic connection extending between certain of said instrumentalities, and said exhaust-pump, and pressure-controlling means for admitting atmospheric air to vary the degree of reduced air-pressure, of means located in said connection and exposed upon one side to the pressure-reducing influence of said exhaust-pump and upon the other side to the pressure-varying effects of said pressure-controlling means for yieldingly resisting the passage of air through said connection, and means 10 located in said connection between the last said means and said exhaust pump and operable independently of the last said means for closing said connection.
15. In a pneumatically operated musical instrument, the combination, with a plurality of pneumatically operable instrumentalities, an exhaust-pump for reducing the air-pressure to effect the pneumatic operation thereof, and pressure-controlling means 20 for admitting atmospheric air to vary the degree of reduced air-pressure effective in one of said instrumentalities, of a pneumatic connection extending between said pressure-controlling means and said one of said instrumentalities on the one hand and said exhaust-pump on the other hand, a valve intercepting said connection and exposed to the air-pressure therein, a spring acting upon said valve to cause it to yieldingly resist the passage of air through said connection, means for adjusting the action of said spring upon said valve, an atmospheric inlet opening into said connection between said valve and said exhaust-pump, 25 a valve closing said inlet, a spring acting upon the last said valve to cause it to yieldingly resist the admission of atmospheric air through said inlet, and means for adjusting the action of the last said spring upon the last said valve.
16. In a pneumatically operated musical instrument, the combination, with a plurality of pneumatically operable instrumentalities, an exhaust-pump for reducing the air-pressure to effect the pneumatic operation thereof, and pressure-controlling means 30 for admitting atmospheric air to vary the degree of reduced air-pressure effective in one of said instrumentalities, of a pneumatic connection extending between said one of said instrumentalities and said exhaust-pump, a valve intercepting said connection and exposed to the pressure-varying effects of said pressure-controlling means, a spring 35 acting upon said valve to cause it to yieldingly resist the passage of air through said connection, means for adjusting the action of said spring upon said valve, an atmospheric inlet opening into said connection between said valve and said exhaust-pump,
- 40 a valve closing said inlet, a spring acting upon the last said valve to cause it to yieldingly resist the admission of atmospheric air through said inlet, and means for adjusting the action of the last said spring upon the last said valve.
- 45 17. In a pneumatically operated musical instrument, the combination, with a plurality of pneumatically operable instrumentalities, an exhaust-pump for reducing the air-pressure to effect the pneumatic operation thereof, a pneumatic connection extending between certain of said instrumentalities and said exhaust-pump, and pressure-controlling means for admitting atmospheric air to vary the degree of reduced air-pressure, of a valve intercepting said connection and exposed upon one side to the pressure-reducing influence of said exhaust-pump and upon the other side to the pressure-varying effects of said pressure-controlling means, a spring acting upon said valve to cause it to yieldingly resist the passage of air through said connection, means for adjusting the action of said spring upon said valve, an atmospheric inlet opening into said connection between said valve and said exhaust-pump, a valve closing said inlet, a spring acting upon the last said valve to cause it to yieldingly resist the admission of atmospheric air through said inlet, and means for adjusting the action of the last said spring upon the last said valve.
- 50 18. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure effective in one of said instrumentalities, of a chamber having separate pneumatic communication with more than one of said instrumentalities and with said exhaust-pump, means located within said chamber and exposed to the air-pressure therein for yieldingly resisting the passage of air from said one of said instrumentalities into said chamber, and means for closing the communication of said chamber with said exhaust-pump.
- 55 19. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure effective in one of said instrumentalities, of a chamber having separate pneumatic communication with more than one of said instrumentalities and with said exhaust-pump, a valve intercepting the communication of

said one of said instrumentalities with said chamber and exposed to the air-pressure therein, a spring acting upon said valve to cause it to yieldingly resist the passage of air through the intercepted communication, means for adjusting the action of said spring upon said valve, an atmospheric inlet opening into the communication between said chamber and said exhaust-pump, a valve closing said inlet, a spring acting upon the last said valve to cause it to yieldingly resist the admission of atmospheric air through said inlet, and means for adjusting the action of the last said spring upon the last said valve.

20. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure effective in one of said instrumentalities, of a chest having a partition separating it into first and second compartments, a port in said partition providing pneumatic communication between said compartments, the first compartment having separate pneumatic communication with more than one of said instrumentalities and the second compartment having pneumatic communication with another of said instrumentalities and with said exhaust-pump, a valve controlling said port, and means located in the first compartment of said chest and exposed to the air-pressure therein for yieldingly resisting the passage of air from said one of said instrumentalities into said compartment.

40. 21. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure effective in one of said instrumentalities, of a chest having a partition separating it into first and second compartments, a port in said partition providing pneumatic communication between said compartments, the first compartment having separate pneumatic communication with more than one of said instrumentalities and the second compartment having pneumatic communication with another of said instrumentalities and with said exhaust-pump, a valve controlling said port, a second valve intercepting the communication of said one of said instrumentalities with the first compartment of said chest and exposed to the air-pressure therein, a spring acting upon said second valve to cause it to yieldingly resist the passage of air through the intercepted communication, and means for adjusting the action of said spring upon said second valve.

22. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure effective in one of said instrumentalities, of a chest having a partition separating it into first and second compartments, a port in said partition providing pneumatic communication between said compartments, the first compartment having separate pneumatic communication with more than one of said instrumentalities and the second compartment having pneumatic communication with another of said instrumentalities and with said exhaust-pump, a valve-controlled atmospheric inlet opening into the second compartment of said chest, a valve controlling the port in said partition, and means located in the first compartment of said chest and exposed to the air-pressure therein for yieldingly resisting the passage of air from said one of said instrumentalities into said compartment.

23. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure effective in one of said instrumentalities, of a chest having a partition separating it into first and second compartments, a port in said partition providing pneumatic communication between said compartments, the first compartment having separate pneumatic communication with more than one of said instrumentalities and the second compartment having pneumatic communication with another of said instrumentalities and with said exhaust-pump, a valve controlling said port, means located in the first compartment of said chest and exposed to the air-pressure therein for yieldingly resisting the passage of air from said one of said instrumentalities into said compartment, an atmospheric inlet opening into the second compartment of said chest, and means for yieldingly resisting the admission of atmospheric air through said inlet.

24. In a pneumatically operated musical instrument, the combination, with a plurality of pneumatically operable instrumentalities, an exhaust-pump for reducing the air-pressure to effect the pneumatic operation thereof, and pressure-controlling means for admitting atmospheric air to vary the degree of reduced air-pressure effective in one

of said instrumentalities, of a chest having a partition separating it into first and second compartments, a port in said partition providing pneumatic communication between said compartments, the first compartment having separate pneumatic communication with more than one of said instrumentalities and the second compartment having pneumatic communication with another of said instrumentalities and with said exhaust-pump, a valve controlling said port, a second valve intercepting the communication of said one of said instrumentalities with the first compartment of said chest and exposed to the air-pressure therein, a spring acting upon said second valve to cause it to yieldingly resist the passage of air through the intercepted communication, means for adjusting the action of said spring upon said second valve, an atmospheric inlet opening into the second compartment of said chest, a valve closing said inlet, a spring acting upon the last said valve to cause it to yieldingly resist the admission of atmospheric air through said inlet, and means for adjusting the action of the last said spring upon the last said valve.

25. In a pneumatically operated musical instrument, the combination, with the pneumatically operable player-action and other pneumatically operable instrumentalities, an exhaust-pump for reducing the air-pressure to effect the pneumatic operation thereof, and pressure-controlling means for admitting atmospheric air to vary the degree of reduced air-pressure available for the operation of said player-action, of a chest having a partition separating it into first and second compartments, a port in said partition providing pneumatic communication between said compartments, the first compartment having separate pneumatic communication with said player-action and another of said instrumentalities, and the second compartment having pneumatic communication with said exhaust-pump, a valve controlling said port, a second valve located in the first compartment of said chest and exposed to the air-pressure therein for yieldingly resisting the passage of air from said player-action into said compartment, and means for adjusting the degree of resistance offered by said second valve.

26. In a pneumatically operated musical instrument, the combination, with the pneumatically operable player-action and other pneumatically operable instrumentalities, an exhaust-pump for reducing the air-pressure to effect the pneumatic operation thereof, and pressure-controlling means for admitting atmospheric air to vary the degree of reduced air-pressure available for the operation of said player-action, of means for predetermining the maximum degree to which the air-pressure shall be reduced and

for preventing variations in the degree of reduced air-pressure available for the operation of said player-action from modifying beyond a predetermined minimum the degree of reduced air-pressure available for the operation of another of said instrumentalities.

27. In a pneumatically operated musical instrument, the combination, with the pneumatically operable player-action and the pneumatically operable damper-lift, an exhaust-pump for reducing the air-pressure to effect the pneumatic operation thereof, and pressure-controlling means for admitting atmospheric air to vary the degree of reduced air-pressure available for the operation of said player-action, of means for predetermining the maximum degree to which the air-pressure shall be reduced and for preventing variations in the degree of reduced air-pressure available for the operation of said player-action from modifying beyond a predetermined minimum the degree of reduced air-pressure available for the operation of said damper-lift.

28. In a pneumatically operated musical instrument, the combination, with three pneumatically operable instrumentalities (1-8-13), an exhaust-pump for reducing the air-pressure to effect the pneumatic operation thereof, and pressure-controlling means for admitting atmospheric air to vary the degree of reduced air-pressure available for the operation of one of said instrumentalities (1), of means (34) for predetermining the maximum degree to which the air-pressure available for the operation of another of said instrumentalities (8) shall be reduced, and means (62) for predetermining the minimum degree to which the reduced air-pressure available for the operation of a third of said instrumentalities (13) may be modified.

29. In a pneumatically operated musical instrument, the combination, with pneumatically operable instrumentalities including the player-action, the music-sheet-propelling motor, and the damper-lift, an exhaust-pump for reducing the air-pressure to effect the pneumatic operation of said instrumentalities, and pressure-controlling means for admitting atmospheric air to vary the degree of reduced air-pressure available for the operation of said player-action, of means for predetermining the maximum degree to which the air-pressure available for the operation of said motor shall be reduced, and means for predetermining the minimum degree to which the reduced air-pressure available for the operation of said damper-lift may be modified.

30. In a pneumatically operated musical instrument, the combination, with three pneumatically operable instrumentalities (1-8-13), an exhaust-pump for reducing

the air-pressure to effect the pneumatic operation thereof, and pressure-controlling means for admitting atmospheric air to vary the degree of reduced air-pressure available for the operation of one of said instrumentalities (1), of means (34) for predetermining the maximum degree to which the air-pressure available for the operation of a second of said instrumentalities (8) shall be reduced, means (62) for preventing variations in the degree of reduced air-pressure available for the operation of said one of said instrumentalities from modifying beyond a predetermined mini-

mum the degree of reduced air-pressure 15 available for the operation of a third of said instrumentalities (13), and means (40) for preventing the action of said pressure-controlling means and the operation of said one or said third of said instrumentalities 20 from modifying the maximum degree of reduced air-pressure available for the operation of said second of said instrumentalities.

In witness whereof, I hereunto subscribe 25 my name this 28th day of March A. D., 1924.

WILLIAM C. COLLIGNON.
